(57) CLAIM

The ornamental design for a upper body garment, as shown and described.

DESCRIPTION

FIG. 1 is a rear right perspective view of a upper body garment showing my new design in an in-use configuration;

FIG. 2 is a rear left perspective view thereof;

FIG. 3 is a rear view thereof;

FIG. 4 is a front view thereof;

FIG. 5 is a left side view thereof;

FIG. 6 is a right side view thereof; and,

FIG. 7 is a top view thereof.

The broken lines immediately adjacent to the shaded area represent unclaimed boundaries of the design. The unshaded regions, demarcated by broken lines, represent unclaimed portions of the upper body garment and form no part of the claimed design. The contrast in shading represents a contrast in appearance only and does not represent any particular color, material, texture or finish. The broken lines showing the remainder of the upper body garment are for environmental purposes only and form no part of the claimed design.
